(57) **CLAIM**

The ornamental design for a light housing, as shown and described.

DESCRIPTION

FIG. 1 is a perspective view of a light housing showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a side elevational view of one side thereof;

FIG. 7 is a side elevational view of the opposite side thereof; and,

FIG. 8 is a rear perspective view thereof.

The broken lines (where present) in all FIGS. illustrate portions of the light housing that form no part of the claimed design.

1 Claim, 7 Drawing Sheets
